UNITED STATES PATENT OFFICE.

HAROLD T. AVERY, OF SAN LUIS OBISPO, CALIFORNIA.

FLYING MACHINE.

Application filed April 21, 1925. Serial No. 24,792.

This invention relates to improvements in the control systems for aeroplanes, and particularly to a control system intended to give easier and more complete control of the machine whatever its state of motion whether flying at high speed, flying at low speed, or moving along the ground. It is desirable in flying at different speeds, to have a control system the sensitiveness of which can be regulated to correspond with the speed of flying. Under high speed flying conditions, it is desirable to reduce the effect of slight movements of the controls, thus reducing the amount of strength or force which the aviator must exert in controlling the machine, and also tending to produce steadier flying. Under low speed flying conditions it is desirable to increase the effect of the movements of the controls, in order to keep the machine under full and ready control in spite of the reduced effect of the air impinging against the control surfaces.

The general object of this invention is to provide an aeroplane equipped with improved controlling means, more complete and of a greater range of sensitiveness than heretofore provided, in order that all the conditions of control outlined as desirable in the preceding paragraph may be attained.

Further objects of the invention will appear hereinafter.

The invention consists in the novel parts and combination of parts to be described hereinafter, all of which contribute to produce an efficient flying machine.

A preferred embodiment of the invention is described in the following specification, while the broad scope of the invention is pointed out in the appended claims.

In the drawings:

Fig. 1 is a diagram of the control system in perspective, showing its relation to the aileron and elevator and also indicating the brakes which are associated with the landing wheels.

Fig. 2 is a perspective upon an enlarged scale, also diagrammatically illustrating details of the control system in the vicinity of the control sticks.

Fig. 3 is a vertical section taken through

the rear control stick in a vertical front and rear plane.

Fig. 4 is a vertical transverse section through the control apparatus and passing through the longitudinal axis of rotation of the control sticks and particularly illustrating details of the controlling means which I prefer to employ for controlling the aileron.

Fig. 5 is a horizontal cross section taken about on the line 5—5 of Fig. 4.

Fig. 6 is a front elevation of an aeroplane embodying my invention and particularly illustrating the construction of the landing wheels.

Fig. 7 is a side elevation of the aeroplane shown in Fig. 6.

Fig. 8 is a longitudinal section through the fuselage of the aeroplane taken in a front and rear direction, broken away, and shown partly in elevation.

Fig. 9 is a vertical section taken through one of the brake drums and illustrating details of the brakes.

Fig. 10 is a plan of the aeroplane with the upper wing and the top of the fuselage removed, and with the planes or wings broken away at each side of the fuselage; portions of the elevator are also broken away.

Fig. 11 is a front elevation illustrating a wheel mounting construction in which the wheels extend above the plane of the lower wing and

Fig. 12 is an end elevation of the aeroplane shown in Fig. 11.

According to my invention, I utilize the system of movable vanes, known as aileron and elevators, customarily used in aeroplane construction, for the control of all vertical movements and rotations or orientations of the machine, and I utilize the means for controlling these vanes, which in practice is the control stick. I provide, however, improved means for connecting the control stick with these vanes, for operating the vanes, and in addition I provide a hand actuated controlling member which may be moved by the aviator at will to vary the leverage of the forces exerted by the control stick.

My control system is very clearly illustrated in Fig. 1. In the drawings, the in-

vention is shown as applied to a dual control system, but it should be understood that my invention is equally applicable to a single control system.

- 5 In practicing my invention as applied to a dual control system, I provide a pair of control sticks 1 and 2 which are mounted to rotate on a longitudinal axis extending longitudinally with the fuselage 3. This 10 longitudinal axis of rotation is preferably a common axis for the two sticks. In addition to this, each control stick is mounted to rotate on an axis transverse to the fuselage. In the present instance, I provide a sleeve 4 which extends longitudinally with the fuselage, and each control stick is provided at its lower end with a yoke, the forks of which are pivotally attached to the sleeve by a transverse pivot pin or bolt 5.
- 15 20 I provide a connection from the control stick to the aileron constructed so that the point of connection can be gradually and continuously moved at will to vary the leverage of the stick.
- 25 For this purpose, associated with the control sticks I provide an actuator which is guided so that it may be moved toward or from the longitudinal axis of rotation, and this actuating means is connected with the 30 vane of the flying machine which is to be controlled; for example, it is connected to the elevator 6 and the aileron 7. In order to accomplish this in a dual control system, the actuating means includes two actuators 35 8, one of which corresponds to each control stick. In Fig. 3, I illustrate the second control stick 2.
- Each actuator 8 is in the form of a nut 40 mounted on an adjusting screw 9 which extends longitudinally of the stick. The stick 2 is provided with a slot 10 on its front side and a similar slot 10 on its rear side, and into these slots the ends of the actuator or nut 8 project. In the case of the forward 45 control stick, there need be only one slot which is on the rear side. These two actuator nuts 8 are connected by a bar 11 which extends longitudinally over the sleeve 4. The actuator nut 8 on the rear control 50 stick 2 is connected by a suitable controlling means with the elevator 6. For this purpose I provide a link 12 which extends back and attaches to an arm 13 on a rock shaft 14, said rock shaft being provided with 55 double arms 15 to which wires or cords 16 attach and extend backwardly, each cord 16 being attached to a corresponding arm 17. One of the arms 17 projects upwardly from the elevator 6 and the other projects 60 downwardly. With this construction, it will be evident that by rocking the control lever forwardly or rearwardly, the elevator will be raised or lowered on its hinge joint 18.
- 65 A hand actuated member and means ac-

tuated thereby are provided for rotating the adjusting screws 9 so as to raise or lower the actuator nuts 8 in unison. This hand-actuated member is preferably independent of the control-stick. For this purpose, I 70 may provide a hand lever 19 near each aviator's position, each of these hand levers being pivoted on the frame of the machine and carrying a vertical disc 20 that rotates when the lever is swung. An endless cord 75 21 passes around these two discs and is guided on pulleys 21^a, its ends being attached to a rack bar 22 which is mounted to slide longitudinally in the sleeve 4. This rack bar engages a pinion 23 attached to 80 the lower end of each adjusting screw (see Fig. 3) so that when the rack is moved longitudinally the adjusting screws will be rotated.

I provide means for connecting the bar 85 11 with the aileron 7 so that when the bar moves further in or further out with respect to the longitudinal axis of rotation, the leverage of the force exerted through the agency of the bar will be varied. In other 90 words, if the bar 11 has been raised considerably, it will operate to produce an increased amount of movement in the elevator and in the aileron for a given movement of the lever.

In order to avoid the necessity for providing a very heavy, rigid construction for the bar 11, I provide an actuator block 24 (see Fig. 2) through which the bar 11 slides freely, and this block is guided so that it 100 can slide in or out with respect to the axis of the sleeve 4. For this purpose, the sleeve is provided with a rigid arm 25 having a slot 26 in which the block fits and slides freely.

The sleeve 4 itself is mounted in a suitable bearing 4^a for rotation on its longitudinal axis. I provide means connected with the actuator block 24, connected with the aileron 7 for controlling them. This means may be a wire or cord 27 extending from the block in either direction and guided on suitable guide pulleys 28, 29, the rear end of each cord being attached to a post 30 projecting down from each aileron. The ailerons are connected together by a cross wire or cord 31 guided around suitable pulleys 32, and the ends of this wire are connected to upwardly projecting arms 33.

It will be evident that when the control sticks are moved to the right or to the left, the cords or wires 27 will be operative so as to swing the ailerons up or down on their hinge joints 34.

At the elevator I provide a vertical rudder 35 connected to the fuselage by a vertical hinge joint 36. This rudder may be swung on its joint through the agency of the dual foot levers 37. These dual levers 37 are connected by tie-wires 38, and the rearmost

dual lever is connected by cords or wires 39, at each side to a post or arm 40 projecting horizontally and laterally from the rudder.

In order to facilitate the landing of the flying machine and overcome a tendency for the machine to tip forward and wreck itself should it encounter any unevenness, obstruction, or soft or loose earth, in the path of the wheels, I provide the aeroplane with two landing wheels 41 of relatively large diameter, and these wheels are rotatably supported on axles 42 (see Fig. 6) at the outer extremities of the wing. The landing wheels 41 may be constructed of any diameter desired, but whereas it has been customary heretofore to place the landing wheels under the lower wing or fuselage, and necessarily therefore of less diameter than the clearance of the wing or fuselage from the ground, I provide landing wheels of greater diameter than such clearance by placing them beyond the ends of the lower wing. Axles 42 may be mounted in any suitable manner on the general framework of the aeroplane. My preferred embodiment of such mounting is shown in Figures 11 and 12, in which the axle is fastened to the under side of lower wing 43^b at the two outer front panel points. An alternate manner of mounting, also coming within the general scope of this invention, is shown in Figures 6 and 7, in which the axles are mounted between the upper plane 43^a and the lower plane 43^b. This latter method of mounting allows of somewhat larger wheels than the former, giving somewhat greater range of safety in lighting and running along the ground. It also gives somewhat greater elasticity for the absorption of impact, but involves greater weight and offers greater wind resistance than the former.

The machine is constructed with the usual posts or struts 44 connecting the upper and lower wings, and the whole structure is braced by the usual diagonal tie-braces or guy-wires 45. The axles 42 are held in position by suitable braces 46. Within the fuselage 3 seats 47 are provided for the aviators, and these seats are located just rearwardly of the corresponding control sticks.

For stopping and steering the machine in "taxi-ing" along the ground, I provide a brake 48 corresponding to each wheel. This construction includes a brake drum 49 (see Fig. 9) rigid with the wheel. Adjacent to the brake drum I provide a brake band 50 which is supported at 51 on an arm 52 projecting from the axle. I also provide a brake lever 53 one end of which is pivotally attached at 54 to one end of the brake band, and it is also attached near this point by means of a link 55 to the other end of the brake band, the construction being such that when the lever is pulled toward the left, as

viewed in Fig. 9, by means of a pull wire 56, the brake band will be contracted upon the brake drum. Each pull wire 56 is guided around suitable guide pulleys 57 and the inner end of each brake wire is attached to the end of the rearmost lever 37 which controls the position of the rudder 35. It should be understood that the dual levers 37 are mounted to swing on substantial pivots at their middle points. This, of course, only permits of one brake being applied at a time, but this is desirable because applying both brakes at once while the machine was moving along the ground at any considerable speed would tend to upset the machine onto its nose. By applying one brake at a time, the machine can be directed toward one side or turned sharply about without aid from persons on the ground and without danger of upsetting, and in this way considerable braking force may be applied and a landing effected on a comparatively small tract of ground.

The mode of operation of the flying machine will be briefly stated:

By swinging either of the control sticks on its transverse pivot 5, the elevator 6 may be swung up or down. By swinging either control stick to the right or to the left, that is to say, by producing a rotation on the longitudinal axis of the sleeve 4, the cords 27 will control the aileron 7. When the aviator desires to increase the leverage through which the controlling force is applied at the control stick, he moves the lever 19 in the proper direction to rotate the adjusting screws in a direction to move the actuator nuts 8 inwardly or toward the sleeve 4. This movement of the actuator nuts 8 inwardly in this way will also adjust inwardly the actuator block 24 which moves in and out in unison with them. Therefore, any adjustment of this character in the actuator nuts will produce the same character of adjustment in the control of the aileron. In this way, by a slight movement of the lever 19, the rack 22 may be moved any desired amount to effect the desired adjustment of the sensitiveness of the flying machine; and to reduce to a minimum the exertion of strength on the part of the aviator in controlling the machine.

In flying with an aeroplane embodying my improvements, it is possible to alight at a somewhat lower speed than would otherwise be possible, because the control can be adjusted to give an increased controlling effect, and because the increase of leverage of controls at high speeds permits of using control surfaces of larger area than would otherwise be practicable, thereby enabling the machine to be controlled though flying at low speed.

It is understood that the embodiment of the invention described herein is only one

of the many embodiments this invention may take, and I do not wish to be limited in the practice of the invention, nor in the claims, to the particular embodiment set forth.

5. What I claim is:—

1. In a flying machine, the combination of a movable vane engaged by the air as the machine advances, a control-stick, means connecting the control-stick with the said vane, 10 and a hand-actuated controlling member mounted to move independently of the control-stick, with means actuated thereby for gradually varying at will the leverage of the force exerted by the control-stick.
15. 2. In a flying machine, the combination of a frame, an elevator, a control-stick, means connecting the control-stick with the elevator for operating the same, and a hand-actuated controlling member pivotally attached to the 20 frame, with means actuated thereby for varying at will the leverage of the force exerted by the control-stick.
25. 3. In a flying machine, the combination of a frame, ailerons, a control-stick, a continuously variable connection connecting the control-stick with the ailerons to operate the same, a movable hand-operated member within reach of the aviator when in his upright position, and means including an adjusting 30 screw controlled by the hand-operated member for gradually and continuously varying at will the point of connection between the control-stick and the ailerons to alter the leverage of the control-stick.
35. 4. In a flying machine, the combination of a frame, a control-stick, an elevator with elevator control means having a variable connection with the control-stick, ailerons with aileron-control means connecting the same to the control-stick, a hand-operated member within reach of the aviator's hand in his upright position, and means actuated by the hand-operated member including an adjusting screw for actuating the variable connection and continuously varying at will the leverage exerted by the control-stick through both of said control means.
50. 5. In a flying machine, the combination of ailerons, a control-stick, means for supporting the control-stick to rotate about an axis, means actuated by the control-stick and connected with the ailerons to operate the same, and a hand-actuated member mounted to move independently of the control-stick, with 55 means controlled thereby for gradually varying at will the distance of said last named means from the axis of rotation to vary the leverage of the force exerted by the control-stick.
60. 6. In a flying machine, the combination of an elevator, a control-stick, means for supporting the control-stick to rotate about an axis, means actuated by the control-stick and connected with the elevator to operate the 65 same, and a hand-actuated member mounted

to move independently of the control-stick, with means controlled thereby for gradually varying at will the distance of said last named means from the axis of rotation to vary the leverage of the force exerted by the 70 control stick.

7. In a flying machine, the combination of ailerons, an elevator, a control-stick, means for supporting the control-stick to rotate about an axis, a member mounted to rotate about said axis with the control-stick, a hand-actuated member independent of the control-stick with means connecting the same to said last named member for varying the distance of the same from the axis of rotation to regulate the leverage of the force exerted by the control-stick, and means connecting said first named member with the ailerons and the elevator.

8. In a flying machine having ailerons 85 and an elevator, the combination of a control-stick, means for supporting the control-stick to rotate about an axis, a member mounted to rotate about the said axis with the control-stick and having adjusting means 90 operating to move the same gradually and continuously toward or from the said axis to regulate the distance of said first named member from said axis, and having means connecting said first named member with the 95 ailerons and the elevator.

9. In a flying machine having ailerons and an elevator, the combination of a control-stick, means for supporting the control-stick to rotate about a longitudinal axis extending 100 longitudinally with the fuselage of the machine, and for rotation about a transverse axis extending transversely of the fuselage, an actuator, means mounted to rotate on the said longitudinal axis with the control-stick and constituting guiding means for guiding the actuator in a substantially radial direction to or from the said longitudinal axis, a hand-actuated member for adjusting the actuator toward or from the longitudinal 110 axis, and means for connecting the actuator with the ailerons and the elevator.

10. In a flying machine having ailerons and an elevator, the combination of a sleeve mounted to rotate on a longitudinal axis extending longitudinally with the fuselage, an actuator, an arm carried by the sleeve with means for guiding the actuator to move toward or from the said longitudinal axis, a control-stick pivotally mounted on a transverse axis on the sleeve, a hand actuated member movable at will and means operated thereby to move the actuator toward or from the longitudinal axis, and means for connecting the actuator to the ailerons and the elevator.

11. In a flying machine having ailerons and an elevator, the combination of a sleeve, means for supporting the same to rotate on a longitudinal axis extending longitudinally 130

- with the fuselage, an arm rigid with the sleeve, an actuator guided on the arm, a control-stick pivotally mounted on the sleeve on a transverse axis, a hand-actuated member movable at will and having means actuated thereby for adjusting the actuator on the arm toward or from the longitudinal axis, and means connecting the actuator with the ailerons and the elevator.
12. In a flying machine having ailerons and an elevator, the combination of a sleeve mounted to rotate on a longitudinal axis extending longitudinally with the fuselage, an arm rigid with the sleeve, an actuator in the form of a block mounted to slide on the arm toward and from the longitudinal axis, a hand actuated member movable at will, means controlled thereby for effecting the adjustment of the actuator block on its arm to or from the said longitudinal axis, a control-stick pivotally mounted on the sleeve on a transverse axis and connected with the block, and means for connecting the block with the ailerons and the elevator.
13. In a flying machine having ailerons and an elevator, the combination of a pair of control-sticks, means for supporting the same to rotate on a longitudinal axis extending longitudinally with the fuselage, and on transverse axes, a movable actuator carried by each control-stick, a hand-actuated member movable at will, means actuated thereby for both moving the said actuators on the control-sticks toward or from the longitudinal axis, and means for connecting the actuators with the elevator.
14. In a flying machine having ailerons and an elevator, the combination of a pair of control-sticks, means for supporting the same to rotate on a longitudinal axis extending longitudinally with the fuselage, and on transverse axes, a movable actuator carried by each control-stick, a hand-actuated member movable at will, means actuated thereby for moving both the said actuators on the control-sticks toward or from the longitudinal axis, means for connecting the actuators with the elevator, another actuator guided to move to or from the said longitudinal axis with the first named actuators, and means for connecting the last named actuator with the ailerons.
15. In a flying machine having ailerons, the combination of a pair of control-sticks, means for supporting the same to rotate on a longitudinal axis extending longitudinally with the fuselage and on transverse axes respectively, a movable actuator carried by each control stick, a bar connecting the same, a hand-actuated member movable at will, means actuated thereby for moving the said actuators along the control sticks toward or from the said longitudinal axis, means for connecting the actuators with the elevator,
- and means connecting the said bar with the ailerons.
16. In a flying machine having ailerons, the combination of a sleeve mounted to rotate on a longitudinal axis extending longitudinally with the fuselage, an arm carried by the sleeve, a pair of control-sticks each attached to the sleeve on a transverse axis and capable of rotating the sleeve on its longitudinal axis, an actuator guided on each stick to move to or from the said longitudinal axis, a hand-actuated member movable at will, with means actuated thereby to adjust the actuators toward or from the said longitudinal axis, a bar connecting the said actuators, an actuator block carried on the bar and having means connected with the sleeve for guiding the same toward or from the said longitudinal axis when the first named actuators are moved toward or from the said longitudinal axis, means connecting the first named actuators with the elevator, and means for connecting the actuator block with the ailerons.
17. In a flying machine, the combination of a control-stick mounted to rotate on a longitudinal axis extending longitudinally with the fuselage, an adjusting screw associated with the control stick and extending substantially radially from the said axis of rotation, an actuator mounted as a nut on said screw, a hand-actuated member movable at will, with means actuated thereby for rotating the said adjusting screw to move the actuator in or out with respect to the said axis, a movable vane carried by the machine, and means connecting the actuator with the movable vane to control the same.
18. In a flying machine having an elevator, the combination of a pair of control sticks mounted to rotate on a longitudinal axis extending longitudinally with the fuselage, an adjusting screw associated with each control stick, an actuator associated with each control-stick and operating as a nut on its corresponding adjusting screw, a hand-actuated member movable at will, means actuated thereby for rotating said adjusting screws to move the actuators in or out with respect to the said axis, and means for connecting the actuators with the elevator.
19. In a flying machine having ailerons, the combination of a rotatable sleeve mounted to rotate on an axis extending longitudinally with the fuselage, a control-stick pivotally attached to the sleeve on a transverse axis, an arm carried by the sleeve, an actuator block guided to slide on said arm, an adjusting screw associated with the control-stick, an actuator guided in the control-stick and operating as a nut on the adjusting screw, means connecting the actuator nut

and the actuator block and operating to move the block in or out when the actuator nut moves in or out, means connecting the actuator nut with the elevator, and means for connecting the actuator block with the ailerons.

20. In a flying machine, the combination of a frame a movable vane engaged by the air as the machine advances, controlling

means for controlling the motion of said vane, and a controlling member movably mounted on the frame for varying at will the leverage of the force exerted by the said controlling means.

Signed at San Luis Obispo, Cal., this 4th day of April, 1925.

HAROLD T. AVERY.
